CLAIM

We claim the ornamental design for a portable camera support, as shown and described.

DESCRIPTION

FIG. 1 is a front perspective view of a portable camera support showing our new design;

FIG. 2 is a rear perspective view thereof;

FIG. 3 is a front view thereof;

FIG. 4 is a left side view thereof;

FIG. 5 is a top view thereof;

FIG. 6 is a rear view thereof;

FIG. 7 is a right side view thereof;

FIG. 8 is a bottom view thereof;

FIG. 9 is a front perspective view of the second embodiment of a portable camera support showing our new design;

FIG. 10 is a rear perspective view thereof;

FIG. 11 is a front view thereof;

FIG. 12 is a left side view thereof;

FIG. 13 is a top view thereof;

FIG. 14 is a rear view thereof;

FIG. 15 is a right side view thereof; and,

FIG. 16 is a bottom view thereof.

It is understood that a portable camera support shown broken away to indicate indeterminate length.
